(57) **CLAIM**

The ornamental design for an umbrella handle, as shown and described.

DESCRIPTION

FIG. 1 is a perspective view of an umbrella handle showing my new design;

FIG. 2 is front elevation view of the handle of FIG. 1;

FIG. 3 is a rear elevation view of the handle of FIG. 1.

FIG. 4 is a first side elevation view of the handle of FIG. 1.

FIG. 5 is a second side elevation view of the handle of FIG. 1;

FIG. 6 is a top plan view of the handle of FIG. 1.

FIG. 7 is an enlarged top plan view of a portion of the handle of FIG. 6; and,

FIG. 8 is a bottom plan view of the handle of FIG. 1.

The broken lines depict portions of the article that form no part of the claimed design. The shading represents flat portions of the claimed design.

1 Claim, 4 Drawing Sheets---
